CLAIM

The ornamental design for an aromatherapy candle, as shown and described.

DESCRIPTION

FIG. 1 is a top, left, front side perspective view of an aromatherapy candle showing my new design;

FIG. 2 is a bottom, right, rear side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the aromatherapy candle that form no part of the claimed design.
